[57] CLAIM

The ornamental design for an oven housing, as shown and described.

DESCRIPTION

FIG. 1 is a front perspective view of the oven housing embodying my new, original and ornamental design;

FIG. 2 is a rear perspective view from one side of the oven housing;

FIG. 3 is a rear perspective view from the oven housing;

FIG. 4 is a side view from one side of the oven housing, the opposite side being substantially a mirror image of that shown except for the handle and the hinges;

FIG. 5 is a view from below of the oven housing; and,

FIG. 6 is an enlarged top view of the oven housing.
